UNITED STATES PATENT OFFICE.

JACOB C. EICHHORN, OF DETROIT, MICHIGAN, ASSIGNOR TO THE VICTOR JAR COMPANY, OF DETROIT, MICHIGAN, A CORPORATION OF MICHIGAN.

CLOSURE FOR VESSELS.

1,042,209.

Specification of Letters Patent. Patented Oct. 22, 1912.

Application filed July 17, 1912. Serial No. 702,886.

To all whom it may concern:

Be it known that I, JACOB C. EICHHORN, a citizen of the United States of America, residing at Detroit, in the county of Wayne 5 and State of Michigan, have invented certain new and useful Improvements in Closures for Vessels, of which the following is a specification, reference being had therein to the accompanying drawings.

10 This invention relates to a closure for vessels and more particularly to means whereby a cover may be secured to a wide mouthed receptacle to form a hermetical joint, without the use of tools or permanent sealing 15 means.

The invention consists in the matters hereinafter set forth and more particularly pointed out in the appended claims.

In the drawings, Figure 1 is a plan view 20 of a vessel and cover provided with securing means that embodies features of the invention; Fig. 2 is a view in elevation, partially broken away and in section, of a portion of the receptacle and cover; Fig. 3 is a view in 25 detail showing the means of securing a clamping band in position; and Figs. 4 and 5 are views in detail showing the construction of the clamping means.

Referring to the drawings, a receptacle 1 30 has an exterior flange 2 around its mouth on which a closure 3 may be placed, the latter being centered by a depending annular rib 4 and being provided with an exterior flange 5 corresponding in contour to the 35 flange 2. A resilient washer 6 of suitable material is interposed between the closure and vessel mouth.

A band 7 of resilient material, sheet metal or the like encircles the flanges and has a 40 plurality of oppositely disposed marginal lugs 8 that are adapted to yieldingly embrace the opposite faces of the flanges 2 and 5 so that when the band is tightened around the flanges the latter are crowded against 45 the interposed washer 6.

A pair of ears 9 are struck up from one end portion of the band and are apertured to receive the outturned ends or pintles 10 of a sheet metal clamping lever 11. The

mating end portion of the band is formed 50 into a tongue 12 with a head 13 interlocking with a longitudinal slot in the body of the lever 11. The tongue has an off-set bend indicated at 14 adjacent the head so that when the parts are in closed position as 55 indicated in Figs. 1 and 4, the parts tend to remain in that position, the line of strain coming within the fulcrum point of the lever pintles. To prevent lateral movement of the end portion on which the lever 11 is 60 fulcrumed guide ears or flanges 14 are formed thereon to yieldingly grip the vessel and closure flanges.

As a result of this construction, a closure is obtained that can be applied without the 65 use of tools and that when so applied, hermetically seals the vessel. The clamping band may be removed and reapplied as desired. Because of the peculiar construction of the band, the mouth of the vessel may 70 be of the full diameter of the vessel as the band pinches down the closure at frequent intervals throughout its periphery regardless of its length.

Obviously, changes in the details of construction may be made without departing from the spirit of my invention and I do not care to limit myself to any particular form or arrangement of parts.

I claim:—

1. The combination with a receptacle having an exterior flange around its mouth, of a closure therefor having a corresponding flange, a resilient band adapted to encircle the superposed flanges and to yieldingly grip 85 them along the outer annular faces thereof, a slotted clamping lever pivotally secured to one end portion of the band, and a head formed on the other end portion to engage the slotted body of the lever, the head being 90 offset from the band to lie against the face of the other end portion when the lever is folded back.

2. The combination with a receptacle having an exterior flange around its mouth, of a closure therefor having a corresponding flange, a resilient band adapted to encircle the superposed flanges, a series of lugs on

the margins of the band adapted to yieldingly grip the flanges and force them together when the band is drawn tight, a slotted clamping lever pivotally secured to one end portion of the band, and a head formed on the other end portion to engage the slotted body of the lever, the head being offset from the band to lie against the face

of the other end portion when the lever is folded back.

In testimony whereof I affix my signature in presence of two witnesses.

JACOB C. EICHHORN.
